UNITED STATES PATENT OFFICE.

ELLSWORTH E. FLORA, OF CHICAGO, ILLINOIS, ASSIGNOR TO SIMPLEX METAL BOUND BOX COMPANY, OF CHICAGO, ILLINOIS, A CORPORATION OF NEW JERSEY.

WIRE-BOUND BOX.

1,042,100.

Specification of Letters Patent.

Patented Oct. 22, 1912.

Application filed July 21, 1911. Serial No. 639,786.

To all whom it may concern:

Be it known that I, ELLSWORTH E. FLORA, a citizen of the United States, residing at Chicago, in the county of Cook and State 5 of Illinois, have invented a new and useful Improvement in Wire-Bound Boxes, of which the following is a specification.

My object is to provide a novel and improved construction of wire-bound box with 10 a view of rendering the box particularly light, strong and durable, as well as attractive in appearance.

In the drawing—Figure 1 is a perspective view of a box or shipping case constructed 15 in accordance with my invention; and Fig. 2, an enlarged fragmentary and sectional view of an end-portion of the box.

The body of the box is constructed of 20 wood, or fiber, sheets forming the top 5, bottom 6, front 7 and back 8, held together by means of end binding-wires 10, and when desired, by an additional intermediate binding-wire. The particular features of 25 novelty lie in the manner of securing the box-end sheets 9, also, in the manner of fastening the cover-sheet to the end-sheets as well as in the peculiar form or construction of the end binding-wires 10. These binding-wires 10 form the sole means of securing 30 the sheets forming the box, and the staples employed are used for the purpose of holding such binding-wires in place. In other words by means of my construction the use of nails or screws to secure the 35 top, bottom, sides and ends of the box together is obviated.

The wires 10 consist of single strands formed at determined intervals with loops 40 11. Each loop has as its base a single twist 12 of the strand and is expanded to give to it decided width. Where the box-ends 9 are to be set in, as indicated, the loops 11 are bent or shaped, between the twists and their outer ends, to form sockets 13 fitting around 45 the end edges of the box-body, and to present expanded inset abutments for the box-ends 9. In practice, the end binding-wire 10 is initially provided with the twists and loops at desired intervals and furnished to 50 the box-maker on reels, while the different sheets cut to proper size may be furnished to him in the knock-down.

To construct the box, the sheets 5, 6, 7 and 55 8, which together form a blank for the box-body, are placed in proper order upon a

flat surface, and the first loop of the wire 10 is turned and straightened out, as shown at 14, then bent over the edge of the cover-sheet 5 and fastened down with a staple 15. The wire is then stretched along the blank, 60 with its sockets 13 passing around and receiving the sheet-edges, and fastened in place by staples 16 driven to straddle the twists 12 close to the straight length of the strand. When the end of the blank is 65 reached, the wire is severed, turned back upon itself, to form a tongue 17, and fastened down with a staple 18. When both end binding-wires have been fastened to the blank as described, an intermediate binding-wire 19, consisting of a single straight strand, may be applied, by fastening it to the blank with staples 20, and turned back upon itself at opposite ends to form the loop 70 21 and tongue 22, as shown. The finished 75 blank is then bent around the box-ends 9, which are caused to bear against the abutments formed by the loops 11 on the sheets 6, 7 and 8, and the ends are secured to those abutments with staples 23. In the box illustrated, comparatively long staples 24 are provided along the upper edge portions of the box-ends to register with the loops 11 on the cover 5. The end binding-wires constitute means, which may be the only means, 80 for holding the sides, bottom and ends of the box in rigid relation, and they also operate as hinges for the cover 5. In the use of the box as a shipping case, the cover may be fastened down by passing the tongues 17, 90 22, through the loops 14, 21, and bending the tongues into hooks. The long staples 24 also form tongues adapted to be passed through the adjacent cover-loops and to be bent into hooks, as indicated. Any suitable 95 seal applied, say, to the hook 22, will operate to safeguard the box-contents in shipment, if desired.

The single-strand end binding-wires formed and fastened as shown and described, produce particularly desirable means for their purpose. Stretching of the wires under longitudinal strain is effectually resisted by the single twists 12, at the bases of the loops, and the staples 16 which hold 100 the twists against the sheet surfaces. All the staples should be clenched upon the inner surfaces of the sheets as they are driven.

The box may be quickly and easily constructed from material in the knock-down, 110

and owing to the absence of cleats, the thinness of the material that may be employed, and single strand binding-wire, it may be particularly light considering its strength 5 and durability. For this and other reasons, as well as on account of its attractive appearance, the box is peculiarly adapted to meet the desires of shippers of certain kinds of merchandise.

10 The foregoing description is intended to convey a clear understanding of my improvements in wire-bound box construction, in what I now believe to be the best form of their embodiment, and no undue limitation 15 should be understood therefrom. It is my intention to claim all that is novel in my invention, and that the claims shall be construed as broadly as the prior state of the art may warrant.

20 What I claim as new and desire to secure by Letters Patent is:

1. A wire-bound box having inset box-ends and a body-portion formed of sheet-material, securing means comprising binding-wires extending around opposite end- 25 portions of the body, each consisting of a

single strand formed at determined intervals with short twists and expanded, inwardly bent loops projecting therefrom and shaped into sockets receiving the edges of 30 said material, and the inset box-ends abutting against said loops, the wires being stapled at said twists to the box-body and at said loops to the box-ends.

2. A wire-bound box having a body-portion 35 formed of sheet material, securing means comprising binding-wires extending around opposite end-portions of the body, each consisting of a single strand formed at determined intervals with short twists and expanded, inwardly bent loops projecting therefrom, box-ends abutting against said loops, the wires being stapled at their twists to the box-body, the loops, excepting those on the cover, being stapled to the box-ends 40 and the cover loops forming eyes, and hooks on the box-ends engaging said eyes. 45

ELLSWORTH E. FLORA.
